ENGINE STARTER GEARING

Glenn S. Spencer, Horseheads, N.Y., assignor to Bendix Aviation Corporation, Elmira Heights, N.Y., a corporation of Delaware

Application October 23, 1957, Serial No. 691,985

4 Claims. (Cl. 290—38)

The present invention relates to engine starter gearing and more particularly to that type in which the initial engagement of the gearing is brought about by axial movement of the starting motor shaft.

In engine starter gearing of this type such as shown for instance in the patent to Buxton 2,396,986 issued March 19, 1946, it has been found desirable to incorporate some form of latching means to hold the motor armature in centered position as long as the starting switch is closed, irrespective of variations in load caused by initial explosions in the engine. This makes it possible to use a decentering return spring of sufficient stiffness to insure against undesired engagement of the pinion due to accelerational forces of the vehicle on which the device is mounted.

It is an object of the present invention to provide starter gearing of the above type incorporating a novel form of positive latching means for holding the armature in centered position during cranking.

It is another object to provide such a device in which the latching means is actuated directly by the solenoid which controls the starting switch.

It is another object to provide such a device in which the latching means is released and moved out of operative position when said solenoid is deenergized.

Further objects and advantages will be apparent from the following description taken in connection with the accompanying drawing in which the figure illustrates a preferred embodiment of the invention in side elevation, partly broken away and in section, the electrical elements being shown partly in diagrammatic form.

In the drawing there is illustrated a starting motor 1 which is adapted to be energized by a battery 2 under the control of a magnetic relay switch indicated generally by the numeral 3. The motor 1 comprises a stationary field 4 and a rotary armature 5 mounted on a shaft 6 which is slidably and rotatably mounted in bearings 7 and 8 in the ends of the motor frame. The armature shaft 6 carries a pinion 9 slidably journaled thereon for movement into and out of mesh with a gear 11 of the engine to be started. The pinion is connected to the armature shaft by an overrunning driving and traversing connection which forms no part of the present invention but which is shown and described in the patent to Buxton above cited.

The armature 5 of the motor is provided with a commutator 12 cooperating with brushes 13 in the usual manner, and a thrust spring 14 is located between the commutator 12 and the end bearing 7 of the motor to thereby normally maintain the armature 5 displaced to the right from centered position with respect to the field 4.

The relay switch 3 is mounted on a threaded extension of the motor bearing 7 as indicated at 15 and is provided with a plunger 10 which is located in alignment with the armature shaft 6 and has a latch member 16, swiveled thereon as indicated at 17. Latch 16 has a plurality of elastic arms with hook-shaped terminals

18 normally engaging the tapered end 19 of the bearing extension 15 whereby the hooks are spread apart wider than the diameter of the armature shaft 6. A spring 21 in the relay 3 normally holds the plunger 10 in the extended position as illustrated.

The relay 3 is provided with a solenoid coil 23 energized from the battery 2 by means of a manual switch 24 and when so energized it moves a contact 25 on the plunger 10 to bridge the stationary contacts 26, 27 and thereby complete the starting motor circuit.

The armature shaft 6 is provided near its end with a tapered latch groove 28 in position to receive the hooks 18 of latch 16 when the relay switch is closed, and when the armature 5 is in centered relation with respect to the field 4 of the starting motor.

In operation, starting with the parts in idle position as illustrated, closure of the manual switch 24 energizes the coil 23 of the relay 3, which attracts the plunger 10 causing closure of the relay switch 25, 26, 27. This movement of the plunger withdraws the hooks 18 of the latch 16 from the tapered extension 19 of the motor bearing and permits them to approach each other to the positions shown in dotted lines in the drawing. The consequent energization of the starting motor causes the armature 5 to center itself with respect to the field 4, thereby moving the armature shaft 6 to the left until the hooks 18 enter the groove 28 in the armature shaft and thereby latch the armature in its centered position.

The longitudinal movement of the armature shaft 6 brings the pinion 9 into initial engagement with the engine gear 11, and the rotation of the motor causes the further translation of the pinion into full mesh with the engine gear and ensuing cranking of the engine in the usual manner. During the cranking operation, the armature is not permitted to drift away from its centered position even though the flux through the motor may temporarily diminish responsive to initial explosions of the engine. The pinion 9 is thus maintained in engagement with the engine gear 11 irrespective of temporary overrunning of the pinion due to false starts of the engine.

When the engine is reliably self-operative, the operator opens the switch 24, thus releasing the plunger 10 which is returned to its idle position by the spring 21, the hooks 18 of the latch being again expanded out of contact with the armature shaft by engagement with the tapered end 19 of the motor bearing. The spring 14 is then free to return the armature to its idle decentered position as illustrated.

Although but one form of the invention has been shown and described in detail it will be understood that changes may be made in the design and arrangement of the parts without departing from the spirit of the invention.

I claim:

1. In an electrical starting system for internal combustion engines a motor having a field and an armature which is shiftable axially into and out of centered position with respect to the field, an armature shaft, a pinion slidably mounted for movement thereon and therewith into and out of mesh with a gear of the engine to be started, an overrunning driving connection from said shaft to the pinion, means for energizing the starting motor including an electro-magnetic starting switch having a plunger in alignment with the armature shaft and spaced axially therefrom, said shaft having a circumferential groove adjacent its end, and a latch member mounted on said plunger and movable thereby on closure of the starting switch into position to engage said groove when the motor armature is in central position.

2. An engine starting system as set forth in claim 1 including further means for disengaging the latch from the motor shaft responsive to opening the starting switch.

3. An engine starting system as set forth in claim 1 including further yielding means urging the motor armature away from its centered position with respect to the field, and in which the electromagnet of said starting switch is sufficiently powerful to hold the armature in centered position by means of the plunger and latch connection, irrespective of variations in the energization of the starting motor.

4. An engine starting system as set forth in claim 2 in which the latch member is elastically expandable, and 10 the means for disengaging it from the shaft comprises a

tapered projection on the motor frame which wedges the latch open when the switch plunger moves to its open position.
